F. D. COVINGTON.

PORTABLE STREET CAR TRANSFER TICKET DISPENSING DEVICE.

APPLICATION FILED JAN. 29, 1908. .

906,110.

Patented Dec. 8, 1908.

UNITED STATES PATENT OFFICE.

FRANK D. COVINGTON, OF MILWAUKEE, WISCONSIN.

PORTABLE STREET-CAR TRANSFER-TICKET-DISPENSING DEVICE.

No. 906,110.

Specification of Letters Patent.

Patented Dec. 8, 1908.

Application filed January 29, 1908. Serial No. 413,173.

To all whom it may concern:

Be it known that I, FRANK D. COVINGTON, a citizen of the United States of America, residing at Milwaukee, in the county of Milwaukee and State of Wisconsin, have invented certain new and useful Improvements in Portable Street-Car Transfer-Ticket-Dispensing Devices, of which the following is a full, clear, and exact description, reference being had to the accompanying drawings, forming part of this specification.

My invention relates to a portable dispensing device for transfer tickets adapted to be carried and used by the conductors of street railway companies, and it has for its object the provision of means whereby absolute protection may be afforded street railway companies against loss through fraudulent issuance of transfer tickets by dishonest conductors employed by such companies.

It is a well known fact that under the systems heretofore in vogue by street railway companies of issuing transfer tickets through their conductors it has been possible for dishonest conductors to make fraudulent use of the transfer tickets, to which they have had free access, and that there has been great loss to such companies through impostures on the part of the conductors. It will be sufficient to here make mention of but one kind of such impostures; namely, that of the conductors of different divisions of street railway lines acting in conjunction with each other in such manner that one conductor is able to record cash fares received from passengers as transfer ticket fares instead of cash fares, and obtain from another conductor a sufficient number of transfer tickets to make his apparent fare receipts as indicated by the registers upon his car correspond with such registers although as a matter of fact he has received fares in cash for which he does not account to the street railway company.

My transfer ticket dispensing device is designed to overcome fraudulent practices, such as that mentioned by street railway conductors, in such manner as to render it impossible for the conductors to issue transfer tickets without having received cash fares therefor, inasmuch as the supplies of transfer tickets carried by the conductors are honest and not freely accessible to the conductors, and are only made accessible singly

by coin controlled mechanism which is actuated by the deposit of coins into the device to release the ticket dispensing mechanism.

The device also provides for the recording of the cash fares received for the issuance of transfer tickets and the issuance of transfer tickets, thus making it incumbent upon the conductors to account to the street railway company according to the numbers of transfer tickets issued by them.

A further object of my invention is to enable street railway companies to dispense with registers upon their cars for the recording of transfer tickets as distinguished from cash fares and provide for the conductors registering all fares in a single register, this being made possible by my improvement, due to the fact that cash fares must be paid before the transfer tickets can be issued by the conductors and consequently the transfer tickets, when received by the conductors and registered, may be regarded, in so far as the conductor is concerned, as cash fares.

Figure I is a view partly in front elevation and partly in vertical section of my improved portable transfer device. Fig. II is a vertical cross section taken on line II—II, Fig. I. Fig. III is a vertical cross section taken on line III—III, Fig. I.

In the accompanying drawings: 1 designates the housing of my device which is subdivided interiorly by a vertical partition 2 to provide a transfer receiving compartment A and a coin controlled mechanism compartment B. Access to the transfer compartment is provided through the medium of a cover 3 that is hinged to the back of the housing and is adapted to be locked in a closed position at the front of the housing, so as to prevent unauthorized access to the compartment by the conductor into whose charge the device is delivered for receiving cash fares and the issuance of transfer tickets in return therefor.

The device is in the form of a box designed to be carried by the conductor and to provide for its being readily carried by him I furnish each device with eyes or loops 4 adapted to receive a strap by which the device may be suspended from the conductor's shoulders.

5 is a money box that depends from the housing 1 and which is designed to be kept

in a closed condition to prevent access thereto by the conductor while the device is in his possession.

6 designates a spool loosely mounted in 5 the housing 1 and on which is wound a strip C of transfer tickets which is preferably perforated in order that when the strip is delivered step by step from the device they may be detached singly from the strip to 10 be issued by the conductor. To permit of the delivery of the transfer strip from the housing 1, I provide an exit slot 7 in the front of the housing and guideways 8 and 9 extending inwardly in the housing beneath 15 and above said slot. In the front of the housing 1 is a sight opening that is closed by a glass or other sight plate 10 through which the transfer strip may be viewed at the interior of the housing and 20 to permit of its being so viewed the upper guide 9 is provided with a sight opening 9', see Fig. III.

11 designates an upper feed roller that is located in the transfer compartment A and 25 12 is a lower feed roller located in juxtaposition to the feed roller 11 and between which the transfer strip passes to be fed through the exit slot of the housing 1. A spindle 13 of the lower feed roller 12 extends 30 through the partition 2 in the housing 1, the compartment B and to the exterior of said housing, and it has secured to it a knob 14 by which the feed roller may be turned in feeding the transfer sheet from the transfer chamber A.

In the coin controlled mechanism compartment B of my dispensing device is a curved coin chute 15 that is open at its upper end to receive coins and is open at its lower 40 end to permit the discharge of coins from the chute into the money box 5.

16 designates a segmental disk fixed to the spindle 13 of the lower feed roller 12 and located in the compartment B. This disk is 45 provided with radial shoulders 17 and 18 which are suitably spaced apart from each other.

19 is a dog that is pivotally mounted on the vertical partition 2 within the compartment B and which is provided with a forwardly extending arm having a nose 20 that is adapted to engage the forward shoulder 17 of the segmental disk 16 after each complete rotation of the feed roller 12 and 55 which serves to hold said roller from renewed rotation until it is freed by the disengagement of said nose therefrom. The dog 19 is also provided with a rearwardly extending inclined trip arm 21 whereby it 60 may be operated and that projects into the coin chute 15 in order that it may be struck by a coin to actuate the dog and elevate the nose 20 out of its normal position in front of the forward shoulder 17 of the segmental disk 16. The dog is further provided with

a depending arm 22 having a foot 22' which is adapted to be moved into contact with the perimeter of the segmental disk 16 for the purpose of limiting the movement of the dog when it is tripped through the medium 70 of the coin that has descended in the coin chute to the trip arm 21.

23 is a spring controlled pawl that normally occupies a position in front of the rear shoulder 18 of the segmental disk 16 75 and serves as a means for preventing retrograde rotation of said segmental disk and the lower feed roller 12 with the spindle of which said segmental disk is associated.

When a transfer ticket is to be issued 80 from my device by a street car conductor he deposits the coin tendered to him in payment of a passenger's fare in the coin chute and the coin descends in said chute until it strikes the trip arm 21 of the dog 19, thereby causing 85 said trip arm to be moved downwardly and the nose 20 of the dog to be elevated sufficiently to permit of the lower feed roller 12 and the segmental disk 16 being rotated for the delivery of a single transfer 90 ticket of the transfer ticket sheet C to the exterior of my device. At the time that the nose of the dog is initially freed from the segmental disk 16, the foot 22' of said dog rests against the segmental disk 16 at a point 95 of its edge which is farthest removed from the axis of the segmental disk, and the dog is therefore not permitted to move a sufficient distance at this time to allow escape of the coin past the trip arm 21. As the segmental disk is turned, however, its rear shoulder 18 passes the point of the foot 22' and the depending arm is permitted to approach more closely to the axes of the segmental disk with the result of the trip arm 100 21 partaking of a further downward movement so that the coin previously resting thereagainst will escape from the trip arm and descend through the chute to the money box 5. After the dog has been relieved by 105 the escape of the coin therefrom it returns to its normal position and the nose 20 thereof is consequently so disposed as to be engaged by the forward shoulder 17 of the segmental disk 16 upon the completion of a single rotation of the lower feed roller 12, whereby the feed roller is only allowed to feed a single 110 transfer ticket of the sheet C to the exterior of the dispensing device to supply the demand of the passenger from whom he has received a cash fare as payment therefor, and which cash fare has been deposited in the money box or till of the device.

It is desirable to provide in my device a register and an audible signal, the former 115 having the utility of indicating the number of transfer tickets issued from the device and the latter indicating the withdrawal of each transfer ticket issued.

24 is a shaft extending across the transfer 120

ticket compartment A and into the coin controlled mechanism compartment B. This shaft has mounted upon it in the compartment A and back of a sight opening in front of the housing 1 an initial recording wheel 25 that may be fixed to the shaft, and a series of supplemental recording wheels 26 that may be loosely mounted upon the shaft and be operated by suitable connection with 10 the initial wheel 25 in a manner similar to that commonly employed in various types of registers and for which no invention *per se* is herein claimed. The shaft 24 has rigidly mounted upon it within the compartment B 15 a ratchet wheel 27 and it has loosely mounted upon it alongside of said ratchet wheel a pawl carrying arm 28 to which is pivoted a pawl 29, see dotted lines Fig. II, that is arranged in engagement with the ratchet wheel 27.

30 is a retracting spring that is connected to the pawl carrying arm 28 and by which said arm is returned to its normal position after it has been moved in a forward 25 direction.

31 is a trip arm extending downwardly from the pawl carrying arm and adapted to be engaged by a radial pin 32 which is carried by a sleeve 16' that extends from the 30 segmental disk 16. Each time that the lower feed roller 12 is rotated for the delivery of a transfer ticket from my device, the radial pin 32 is rotated with the spindle of said lower feed roller and acts to impart a 35 forward movement to the trip arm 31 with the result of moving the pawl carrying arm forwardly. As a consequence, the pawl 29 acts upon the ratchet wheel 27 to impart a partial rotation to the registering wheel 40 shaft 24 for the actuation of the recording wheels thereon and immediately after this action has taken place, the radial pin 32 escapes from the trip arm 31 and the pawl carrying arm 28 is returned to its normal 45 position by the retracting spring 30. The trip arm 31 is therefore returned to its nor-

mal position ready to be engaged by the radial pin 32 upon the next rotation of the lower feed roller 12 for the delivery of the transfer ticket.

50

I claim:

1. A portable ticket dispensing device comprising a housing, adapted to be carried by a conductor, provided with a chamber for holding a strip of tickets, and an exit for 55 said tickets, lower and upper feed rollers for discharging the tickets through the exit, a segmental disk having forward and rear radial shoulders and fixed to the spindle of the lower feed roller, means for rotating the 60 lower feed roller, and a pivoted dog provided with a forwardly extending arm having a nose adapted to engage the forward shoulder of the segmental disk, a depending arm having a foot adapted to engage the 65 rear shoulder of the segmental disk, and a rearwardly extending trip arm whereby the dog is operated.

2. A portable ticket dispensing device comprising a housing, adapted to be carried by 70 a conductor, provided with a chamber for holding a strip of tickets, and an exit for said tickets, lower and upper feed rollers for discharging the tickets through the exit, a segmental disk having forward and rear 75 radial shoulders and fixed to the spindle of the lower feed roller, means for rotating the lower feed roller, a pivoted dog provided with a forwardly extending arm having a nose adapted to engage the forward shoulder of the segmental disk, a depending arm having a foot adapted to engage the rear shoulder of the segmental disk, and a rearwardly extending trip arm whereby the dog 80 is operated, and a spring controlled pawl 85 located in front of the rear shoulder of the segmental disk.

FRANK D. COVINGTON.

In presence of—

MARIE E. KEARNEY,
WARDELL MOYER.
